(57) **CLAIM**

The ornamental design for the firearm grip panel pair, as shown and described.

DESCRIPTION

FIG. 1 is a right, front, top perspective view of a right side firearm grip panel of a pair of right and left side firearm grip panels attached to a firearm showing my new design, the left side firearm grip panel not being visible from this view; FIG. 2 is a left, front, top perspective view of a pair of right and left side firearm grips for a firearm of FIG. 1 with the firearm omitted;

FIG. 3 is a right side elevation view of a right side firearm grip panel of FIG. 1 with the firearm omitted;

FIG. 4 is a left side elevation view of a left side firearm grip panel FIG. 1 with the firearm omitted;

FIG. 5 is a front elevation view of the pair of right and left firearm grip panels for a firearm of FIG. 1 with the firearm omitted;

FIG. 6 is a rear elevation view of the pair of right and left firearm grip panels for a firearm of FIG. 1 with the firearm omitted;

FIG. 7 is a bottom plan view of the of the pair of right and left firearm grip panels for a firearm of FIG. 1 with the firearm omitted; and

FIG. 8 is a top plan view of the pair of right and left firearm grip panels for a firearm of FIG. 1 with the firearm omitted; and,

FIG. 9 is a perspective view of the surface texture of FIG. 1 shown enlarged.

The broken lines showing portions of the design in all figures are included for the purpose of illustrating environment and unclaimed features and forms not part of the claimed design. The relative density and proportions of the surface treatment is accurately illustrated in FIGS. 3 and 4. For practicality FIGS. 1,2 and 5 through 9 shows a token representation of the surface treatment. The texture pattern sample illustrated in FIG. 9 is applied uniformly within the area circumscribed for the texture; except in the areas marked out for exclusion from the claim.

1 Claim, 6 Drawing Sheets
